UNITED STATES PATENT OFFICE.

JOSEPH A. GROEBLI, OF NEW YORK, N. Y., ASSIGNOR TO THE KURSHEEDT MANUFACTURING COMPANY, OF SAME PLACE.

MACHINE FOR PLAITING OR GOFFERING FABRICS.

SPECIFICATION forming part of Letters Patent No. 637,865, dated November 28, 1899.

Application filed April 19, 1899. Serial No. 713,552. (No model.)

To all whom it may concern:

Be it known that I, JOSEPH A. GROEBLI, residing in the borough of Manhattan, city, county, and State of New York, have invented 5 certain new and useful Improvements in Machines for Plaiting or Goffering Fabrics, of which the following is a specification.

My invention relates to machines for plaiting or goffering fabrics in the piece; and it consists in a machine having a traveling heated surface with a wire or band impinging thereon and moving therewith and a fabric-reefing device located at about the point of entry of the fabric between the heated surface and 15 wire.

Other features of the invention will be pointed out in the claims.

In the drawings I have shown a machine in which my invention is embodied.

20 In the drawings, Figure 1 is a plan view of the machine. Fig. 2 is a front view or elevation thereof looking in the direction of travel of the fabric. Fig. 3 is a vertical sectional elevation, the section being taken on line 3 3 25 of Fig. 2. Fig. 4 is an end view of the machine looking from the right—that is to say, in the direction of the arrow on Fig. 2. Fig. 5 is a fragmentary detail front view of a fabric-guide employed when narrow goods are 30 operated upon; and Fig. 6 is a section on line 6^a 6^a of Fig. 5, showing the fabric-guide in section.

Before describing the machine in detail I would state that in general the machine embodies a moving hot cylinder or surface with 35 lengths of wire bearing upon a portion thereof and traveling at a rate of speed about equal to the surface speed of the cylinder or surface. The goods enter and are carried along 40 between the cylinder and the wires and are laterally shirred, plaited, or goffered by what I term "reefing-wheels," which travel at a greater rate of speed than the cylinder, producing plaits or puckers in the fabric at or 45 about the point where the goods enter between the cylinder and the wire bearing upon the surface thereof. The remainder of the machine consists of various mechanical organisms for imparting motion to the cylinder, 50 wire, and reefing wheel or wheels and for suitably guiding and drying the fabric. I

have also shown a means for applying a cord to the plaited or goffered fabric in the recesses or depressions therein produced by the reefing-wheels or wire.

55 In the drawings, A designates the frame of the machine, upon which the parts are supported. B indicates the cylinder, which receives heat from a suitable heating device, (shown herein as a suitable gas-burner C.) 60 The cylinder is journaled in the frame A and is provided with a peripheral gear D, from which motion is imparted to the rollers for propelling the wire. E is the driving-shaft of the machine, from which motion is transmitted 65 to the various parts. This shaft E is provided with a driving-pulley e, which is suitably driven by a belt e', and is further provided with a pinion e², which meshes with a gear e⁴ on the shaft x. The shaft x drives 70 two independent sets of mechanism, one being the cylinder B, which drives the wire-rollers and the cord-attaching rollers, and the other the train of gearing which drives the reefing wheel or wheels. To the shaft x is 75 secured a pinion e², which meshes with the gear D of the cylinder B, and the gear e⁴ on the same shaft meshes with the intermediate gear e⁵, which in turn meshes with the gear e⁶ on the shaft e⁷, upon which the reefing-wheels e⁸ are mounted. The shaft e⁷ is capable of a slight lateral adjustment, which is effected by slides e⁹, working in guides e¹⁰, 80 provided with adjusting-screws e¹¹, preferably acting against springs placed in the slides e⁹. A series of rollers a b c d, Fig. 3, are journaled in the frame of the machine, over which rollers the wire is carried, being wound partly around said rollers. These rollers are 85 driven from the cylinder-gear D at the same surface speed as the said cylinder, the shafts of the rollers being provided with pinions a' b' c' d', respectively, which mesh with the cylinder-gear D, and are thus driven at the same peripheral speed as the cylinder-gear. 90 The shaft d² of one of these rollers is provided with a pulley d³, which is connected by a belt d⁴ with a pulley f', which is carried on a shaft f at the top of the machine. The shaft f (see Fig. 2) is provided with a pair of wire-drums f² f³, which receive and carry the ends 95 of the wire. The drum f³ is secured to the 100

shaft, while the drum f^2 is mounted loosely thereon and is provided with a suitable strap-brake or other brake device f^4 , which serves to keep the wire under tension.

5 In my improved machine I employ one continuous length of wire i , which is wound off of one drum—say the drum f^2 —passes through the machine back and forth around the rollers $a b c d$, through guide l' , and is wound onto the drum f^3 in a continuous manner, adjacent lengths of wire being arranged in pairs to coincide with the grooves e^2 in the reefing-wheels e^8 , as shown in Figs. 2 and 5. By reference to the plan view, Fig. 1, and also to 15 the front elevation, Fig. 2, it will be seen that the single continuous wire is wound in such a manner in the machine as to present the effect of a number of continuous endless bands of wire. I prefer to use a single continuous length of wire, as a construction embodying a number of separate endless bands has many drawbacks, as I have ascertained by experiment. The course of the wire in the machine is as follows, particular reference being had to Fig. 3: In this figure the wire i upon coming off the drum f^2 passes around part of the circumference of the roller b , around the portion of the circumference of the cylinder intervening between the points 20 $g h$, thence around part of the circumference of the roller d , thence around part of the circumference of the roller c , thence around part of the circumference of the roller a , thence around part of the circumference of the roller b , again to the drum and rollers $d c a b$, &c., in succession through the machine. When the wire has thus been threaded through the machine to the opposite end, (see plan view, Fig. 1,) it is then passed through 25 guide l' to the drum f^3 and secured thereto, so that when the various parts of the machine rotate the wire will be removed from the drum f^2 , passed through the machine as indicated, and finally wound upon the drum f^3 . 40 45 It will be understood that when the main shaft of the machine is rotated the drums, cylinder, reefing-wheels, and rollers will be rotated in the direction of the arrows in Fig. 3, the wire moving in the same direction at the same rate of speed and that the reefing wheel or wheels, which impinge upon the fabric on the drums, will receive a greater peripheral speed of rotation than the surface speed of the cylinder. The fabric-guide k is 50 clearly shown in Figs. 3, 5, and 6. Usually there are several fabric-guides when several strips of fabric j are being operated upon, which fabric-guides are carried by a bar k' , extending across the machine and carried by 55 brackets or supports k^2 . These fabric-guides are preferably for certain classes of work of the general form shown in Fig. 6—that is to say, in the form of a flattened tube having the internally-projecting rib k^3 . A steam-box F may be employed to steam or moisten the goods immediately before they enter the machine, which goods may be guided in front

of the steam-box by a guide-bar l . A series of heated cord-attaching rollers m may be provided upon a suitable support m' in the vicinity of the cylinder and arranged to bear upon the fabric being operated upon on the cylinder and supplemented by cord-guides m^2 , which guide gummed or moistened cords n to the cord-attaching rollers. The machine is primarily designed to produce a goffered or puckered fabric having lines of lateral plaits intervening between puckered portions. The lines of plaits or folds are produced by the conjoint action of the reefing-wheels and the cylinder and the wire.

In the drawings I have shown a number of narrow fabrics being operated upon by the machine, and in this instance the puckered portion forms the center of the fabric, being produced therein by the rib k^3 , which puckered portion is flanked on either side by plaited or folded portions produced by the agency above mentioned. In the normal operation of the machine the fabrics j (see Fig. 4) pass in front of the steam-box F and are thereby steamed or moistened, pass under the guide-bar l , and thence to the cylinder, passing beneath the reefing-wheel (see Fig. 3) and being held firmly to the cylinder between the points g and h by the wires, thence pass downward beneath the roller d and are delivered at the point o . The reefing wheel or wheels, as before stated, travel at a greater rate of speed than the cylinder, and thereby reef, fold, or plait the fabric laterally along lines running longitudinally of the fabric. It will be understood that the reefing-wheels may be replaced by equivalent mechanism without departing from the spirit of my invention and that the heat of the cylinder serves to dry the fabric, and thereby fix the plaits and puckers therein.

What I claim, and desire to secure by Letters Patent, is—

1. In a machine of the character described, the combination of a heated surface, wires bearing upon the said surface with means for driving the wires and the heated surface and a fabric-reefing device located immediately in front of the point where the heated surface and wires contact with each other, substantially as described and for the purposes set forth.

2. In a machine of the character described, the combination of a heated surface, wires bearing upon the said surface with means for driving the wires and the heated surface at the same rate of speed, and a fabric-reefing device located at or near a place or point where the heated surface and wires contact with each other, and a suitable fabric-moistening device and a fabric-guide for respectively moistening and guiding the fabric.

3. In a machine of the character described, the combination of a rotating heated cylinder, a wire bearing upon a portion of the surface of said cylinder, means for driving the wire and cylinder at the same rate of speed

and a reefing wheel or wheels for reefing or 5 puckering the fabric and means for driving the reefing-wheel at a greater rate of speed than the surface speed of the cylinder, substantially as described and for the purposes set forth.

4. In a machine of the character described, the combination of a plurality of drums, a moving heated surface and a continuous wire 10 passing through the machine back and forth over a portion of the heated surface, said wire being so secured at one end to each drum as to be driven thereby, whereby the wire will be wound off one drum, traverse the machine 15 and be wound on the other drum, substantially as described and for the purposes set forth.

5. In a machine of the character described, the combination of a rotating heated cylinder, a continuous wire carried back and forth 20 over a portion of the surface of the said cylinder with means for driving the said cylinder and wire, adjacent individual lengths of the said wire moving in the same direction

traversing the cylinder being arranged in 25 pairs and reefing-wheels coöperating individually with the pairs of lengths of wire and means for driving the said reefing wheel or wheels at a higher rate of speed than the surface speed of the cylinder.

6. In a machine of the character described, the combination of a rotating heated cylinder, a wire traversing a portion of the length 30 of the said cylinder with means for driving the said wire at the same speed as the surface speed of the cylinder and a reefing wheel or wheels located at or about the point of entry 35 of the goods between the wire and the cylinder and means for driving the reefing wheel or wheels at a higher rate of speed than the 40 surface speed of the cylinder, substantially as described and for the purposes set forth.
